[57] CLAIM

The ornamental design for a removable cover for windshield wiper well on vehicles, substantially as shown.

DESCRIPTION

FIG. 1 is a perspective view of a removable cover for windshield wiper well on vehicles showing my new design; it being understood that the broken lines are for illustrative purposes only;

FIG. 2 is a greatly enlarged cross-sectional view thereof taken along line 2—2 in FIG. 3;

FIG. 3 is an enlarged top perspective view thereof; and FIG. 4 is an enlarged bottom perspective view thereof.
